L. D. Tonne,

Cutter Head.

No 14,263.

Patented Feb. 12, 1856.

UNITED STATES PATENT OFFICE.

LOISON D. TOWNE, OF WORCESTER, MASSACHUSETTS.

CUTTER-HEAD FOR PLANING-MACHINES.

Specification of Letters Patent No. 14,263, dated February 12, 1856.

To all whom it may concern:

Be it known that I, LOISON D. TOWNE, of Worcester, in the county of Worcester and State of Massachusetts, have invented certain new and useful Improvements in Cutter-Heads for Cutting Regular or Irregular Forms; and I do hereby declare the following to be a full, clear, and exact description of the same, reference being had to the accompanying drawings, in which—

Figure 1 represents a perspective view of a solid head, with the cutters and braces removed. Fig. 2, represents a central vertical section through the same, with the conical plug in full. Fig. 3, represents one of the braces detached. Fig. 4, is a horizontal section through the head, as it appears when put together. Figs. 5 and 6, represent modifications of the same. Figs. 7, 8, 9, 10, 11, 20 12, represent by varied views a modification of the general plan wherein the head is made sectional, instead of solid, but the same principle of construction retained, and to which figures more particular reference will 25 be hereafter made.

Similar letters of reference where they occur in the several figures denote like parts in all.

The nature of my invention relates to the 30 construction of a cutter head, which possesses great strength and durability, with facility for readily changing it for the various purposes for which it is designed, whether for cutting plain surfaces, or for 35 moldings, as will be hereafter explained.

To enable others skilled in the art to make and use my invention, I will proceed to describe the same with reference to the drawings.

40 A, Figs. 1, 2, 4, 5, represents a solid head of steel or iron, in which a central mortise, α Fig. 1, is made, for the reception of the cutters and braces. When plain surfaces are to be dressed, straight edged cutters are 45 used, and when moldings are to be cut, the cutters should have upon their edge or edges, the shape of the desired molding in reverse. In a longitudinal direction through the cutter head, is made a conical, tapering or 50 wedge shaped hole or opening b , through which passes a similarly formed plug B , having a male screw c cut upon it, which takes into a female screw made in the opening in the cutter head, for the purpose of 55 holding or wedging the cutters, through the intervention of suitable braces or supports,

in the cutter head, as follows: C, C, represent two braces, which, after the cutters d , d , are placed within the mortise, and against the cheeks of the cutter head, are slipped 60 into the mortise, and rest against said cutters. The opposite faces of these braces are rounded out conically, or tapering, as seen at e , Fig. 3, so that when placed within the mortise of the cutter head, they will form a 65 continuation of the conical, or tapering hole through said head. When the cutters and braces are thus placed within the mortise in the head—the edges of the cutters, projecting beyond the periphery of the head, sufficiently far, to take the desired chip or shaving 70 from the material to be dressed, the conical plug B is then introduced, and run down, by means of its screw thread, which spreads the braces C, C, and jams them tight 75 up against the cutters, and thus firmly holds them in their places. By this method of clamping the cutters in their places, there is no necessity of screw, or other holes through them, and they can consequently be resharpened, and set forward, so long as there 80 is sufficient of the plate left, for the braces to bear against.

A small groove f , is made along that edge of each of the braces, (as seen in Figs. 4, 8, 10,) which is next the cutter, for the purpose of throwing out the clips or shavings, and which also serves, to a certain extent, the purpose of caps, to the cutters.

When the material to be worked admits 90 of a deeper hold, or cut, than would be given by the braces C, C, as shown in Figs. 4, 8, where they entirely close up the cylinder, I use braces C', as seen in Figs. 5, 6, having their edges g , beveled off, so as to leave a 95 recess in front of the cutting edges, of greater magnitude than those on C, C.

Figs. 7, 8, 9, represent a modification of the above described plan, on a larger scale wherein the head instead of being solid, is 100 sectional, being composed of the side pieces h , h , and top and bottom plates i , i , which are held together by the screws j , j , and conical points k , k , which latter take into 105 corresponding conical holes l , l , Fig. 10, in the split or divided braces C'', C'', and thus spread them against the cutter plates. And in connection with these conical screws or points, may also be used, the conical plug B', or the plug may be used without the 110 screws, as in the previously described case, the same general principle being involved

viz: the tapering, or wedge shaped form of one piece, holding or fitting against a similarly shaped form in the adjoining piece.

The braces C'', C'', Figs. 8, 10, have projecting pieces *r*, *r*, on their ends, which correspond in thickness with the cutter plates, so that as the cutters are forced forward (which may be done through the holes *s*, *s*, Fig. 10, in said projecting pieces) the heel 10 of the brace shall not tip, but maintain its position, so long as any of the cutting plate remains for them to bear against.

The side pieces *h*, *h*, have a conical recess *m* turned upon them at each end, and upon 15 the ends of the braces C'', C'', are formed projections *n*; and upon the underside of the cap plates *i*, *i*, is turned a conical flange *O*, Fig. 7, which fits over the side pieces, and braces, and when the screws are tight up, or 20 the plug introduced, one or both, every part is rigidly united, the conical points tending to draw in and hold the side pieces, while the plug tends to force them out. The cutters are held in a manner similar to that de- 25 scribed in Figs. 1, 2.

Figs. 11, 12, represent a solid brace or center piece. When this is used the side pieces (*h*, *h*) are drawn up against the center piece, thus clamping the cutters between 30 them, instead of forcing the center or braces against the sides; which is merely reversing the functions of the two parts.

D represents a mandrel, upon which the 35 cutter head may be used, and held by the nut E. Or, the cutter head may be screwed

on to the end of a shaft, as may best adapt it for the special purpose for which it may be designed.

I have represented the cutter head as susceptible of being divided into two sections. 40 It may be divided into three or more, with equal facility, and when used for sash sticking I contemplate making it in three sections and using three cutters. To make these cutter-heads, any useful shop machine, and applicable to the varied duties they are to perform, they must be susceptible of various changes, and should be easily made, and always retain their rigidity, as their speed is necessarily high. Such a cutter head I believe I have made, possessing great strength, 45 durability, and capacity for ready changes.

Having thus fully described the nature of my invention and shown how the same is constructed, I would state that I do not 50 claim a wedge for holding, or spreading the cutters as this is not new, but

What I do claim herein as new and desire to secure by Letters Patent is—

The clamping, or holding of the cutters, 60 between the brace and sides of the cutter-head, by means of the conical or wedge shaped form of the plug, and braces, or their equivalents, and whether said head be solid, or made in two or more sections, substan- 65 tially as described.

L. D. TOWNE.
